SASH CORD HOLDING PLUG

Eugene Leicht and William Kugel,
Brooklyn, N. Y.

Application January 22, 1934; Serial No. 707,686

4 Claims. (Cl. 16—205)

This invention relates to new and useful improvements in a sash cord holding plug.

The invention has for an object the construction of a sash cord holding plug which is adapted to provide for convenient and easy changing the sash cords of windows.

Still further the invention particularly proposes the teaching of a method for changing the sash cords or chains of windows without the necessity of removing the sash from the window frame.

As another object of this invention it is proposed to provide a tubular member for insertion into the front face of a sash having an edge groove extended in from the top for the sash support cord or the like and slightly to the side of said groove, and having a side opening communicating with said groove for the sash cord to pass.

Still further the invention proposes the provision of a plug for closing the front end of the tubular member mentioned in the previous paragraph.

As another object of this invention it is proposed to provide a hook member of flexible material adapted to be inserted through the open top of the groove in the sash and capable of entering the tubular member previously described and engaging a loop element of flexible wire connected with the sash cord or chain or other element so that the cord, chain or other element may be easily threaded through the tubular member and the groove of the sash.

Furthermore it is also proposed to so construct the window frame that the counter-weight may be easily reached to permit attachment and changing of the sash cords, chains and the like.

Furthermore this invention also proposes the construction of a sash cord holding plug which comprises an outer tubular member and an inner tubular member, both of these being provided with side openings for the passing of the sash cord or the like, and an arrangement for moving these tubular members longitudinally relative to each other to cause the gripping of the sash cord, chain and the like.

Still further the invention proposes the construction of an article as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a front elevational view of a window frame and sash equipped with apparatus according to this invention. 5

Fig. 2 is a fragmentary enlarged detailed elevational view of the upper corner of the sash.

Fig. 3 is a horizontal sectional view taken on the line 3—3 of Fig. 2.

Fig. 4 is a perspective view of the sash cord holding plug, per se. 10

Fig. 5 is a horizontal sectional view taken on the line 5—5 of Fig. 2.

Fig. 6 is a fragmentary elevational view of a portion of the window frame seen as though looking in the direction of the line 6—6 of Fig. 1. 15

Fig. 7 is a fragmentary view similar to Fig. 5 but illustrating another embodiment of this invention.

Fig. 8 is an elevational view of the inner tube 20 illustrated in Fig. 7.

Fig. 9 is an elevational view of the hook element used for threading the sash cord.

Fig. 10 is an elevational view of the loop element associated with the sash cord. 25

Fig. 11 is a sectional view of the upper portion of the window sash, this view being similar to the portion illustrated in Fig. 2, but illustrating a chain sash support associated with the mechanism shown in Figs. 7 and 8. 30

The reference numeral 10 indicates a window frame of any design and construction which may be provided with window sashes, such as sash 11 adapted to be slidably guided in vertical grooves arranged upon the inner sides of the frame. The base strip of these grooves is indicated by reference numeral 12. While only one window sash has been illustrated, this was done simply so as not to confuse the drawing, in practice it being necessary that an inner and outer sash be provided. Sash support cords 13 are shown engaged over wheels 14 supported upon the top portion of the base strip 12. The outer ends of these cords 13 are attached upon the window sash 11 while the inner ends are connected with the counter-weights 15. A feature of this invention resides in the manner in which the outer ends of the cords 13 are attached upon the sash 11. 35

More particularly the sash 11 is formed at the sides with grooves 16 extended in from the top 50 and down a short distance. A tubular member 17 is inserted into the front face of the sash 11 slightly to the side of the groove 16 and is provided with a side opening 18 communicating with the groove 16. The cord 13 passes down 55

through the groove 16 and into the side opening 18 into the interior of the tubular member 17. The inner end of the sash cord 13 is formed into a knot 19 within the tubular member so as to hold this end fixed upon the sash. A plug 20 is provided for closing the front end of the tubular member 17 and is threadedly engaged into the inner diameter of the tubular member.

Each of the base strips 12 is provided with removable sections 21 adapted to give excess to the interior of the frame in which the counterweight 15 moves. Each removable section 21 is formed with top and bottom flange portions 22 through which screws 23 engage for the purpose of detachably securing the section upon the strip. Each section 21 is provided with front recessed openings 24 facilitating the gripping of the section during removal. These removable sections 21 are located low upon the window frame so that should the sash cords break, these sections may be removed and the sash weight reached.

The advantage of this invention may best be understood by assuming one of the sash cords 13, in Fig. 1 to have broken and it is now desired to replace this cord. First the plug 20 is removed from the tubular member and the broken portion of the sash cord 13 drawn out from the open end of the tubular member. Next the screws 23 are removed and the removable section 21 removed so that the counterweight 15 may be taken out. The broken cord is then removed from its counterweight. A new cord may then be connected with the sash 11 without removing the sash from the window frame. To accomplish this it is necessary that some implement such as hook 25 illustrated in Fig. 9, constructed of flexible wire, be engaged into the upper open end of the groove 16 and extended down until the hook portion engages through the opening 18 into the tubular member 17. Next a flexible wire 26 should be attached upon the end of the new sash cord 27. The flexible wire 26 is formed with a loop 28 at its end. The loop 28 is engaged upon the hook 25 and then the hook drawn upwards so as to thread the new cord 27 through the opening 18 and the groove 16.

This new cord is then engaged over the wheel 14 and extended down the opening in the window frame until the end can be drawn out through the opening produced by the removal of the section 21. The counterweight is then attached to this end. Next the cord is drawn through the tubular member 17 until the counterweight is at the proper position, that is, when the sash cord is of the proper length. A knot is then formed upon the end of the sash cord and this knot is allowed to engage within the tubular member 17. This knot serves to attach the sash cord upon the sash. The plug 20 is then replaced.

In Figs. 7 and 8 another embodiment of the invention has been disclosed in which an arrangement is provided to grip the end of the sash cord eliminating the necessity of forming a knot, or working in conjunction with the knot to securely hold the end of the sash cord. The construction is substantially identical to that previously described except for the provision of an inner tubular member 30 slidable within the tubular member 17 and formed with an opening 31 adapted in a certain position of sliding to align with the opening 18. This opening 31 has one of its sides formed with gripping elements 32 comprising projecting teeth.

A resilient means such as a spring 33 is engaged within the tubular element 17 and acts

against the inner tubular member 30 to urge it outwards. The outer end of the tubular element 30 is reduced and engages against the plug 20 in such a manner that when the plug is engaged in place on the tubular member 17 the inner tubular member 30 will be forced inwards against the action of the spring 33 so that the teething or gripping elements 32 engage the cord and clamp the cord in position.

In Fig. 11 a chain 13' is shown substituted for the cord 13. The action is identical, that is, the gripping elements 32 may engage upon portions of the chain and so hold the end of the chain fixed in position. This gripping arrangement is of exceptional advantage when a chain is used in that then it is not necessary to form the end of the chain into a knot, which quite often is very difficult to do.

While we have shown and described the preferred embodiment of our invention, it is to be understood that we do not limit ourselves to the precise construction herein disclosed and the right is reserved to all changes and modifications coming within the scope of the invention as defined in the appended claims.

Having thus described our invention, what we claim as new and desire to secure by United States Letters Patent is:—

1. A sash cord holding plug, comprising a tubular member for insertion into the front face of a sash having an edge groove extended in from the top for the sash support cord or the like, and slightly to the side of said groove and having a side opening communicating with said groove for the sash cord to pass, compressible means within said tubular member for clamping said sash cord when depressed and a plug closing the front end of said tubular member and adapted to operate said compressible means when engaged in position.

2. A sash cord holding plug, comprising a tubular member for insertion into the front face of a sash having an edge groove extended in from the top for the sash support cord or the like and slightly spaced to the side of said groove and having a side opening communicating with said groove for the sash cord to pass, an inner tubular member slidable in said tubular member and having an opening with gripping elements aligned with said opening, resilient means for urging said inner tubular member outwards, and a plug for closing the front end of said outer tubular member and for forcing said inner tubular member inwards for engaging the gripping elements upon a cord or the like passing through said openings.

3. A sash cord holding plug, comprising a tubular member for insertion into the front face of a sash having an edge groove extended in from the top for the sash support cord or the like and slightly spaced in the side of said groove and having a side opening communicating with said groove for the sash cord to pass, an inner tubular member slidable in said tubular member and having an opening with gripping elements aligned with said opening, resilient means for urging said inner tubular member outwards, and a plug for closing the front end of said outer tubular member and for forcing said inner tubular member inwards for engaging the gripping elements upon a cord or the like passing through said openings, said resilient means comprising a spring arranged behind said inner tube.

4. A sash cord holding plug, comprising a tubular member for insertion into the front face of a sash having an edge groove extended in from the top for the sash support cord or the like and slightly spaced to the side of said groove and having a side opening communicating with said groove for the sash cord to pass, an inner tubular member slidable in said tubular member and having an opening with gripping elements aligned with said opening, resilient

means for urging said inner tubular member outwards, and a plug for closing the front end of said outer tubular member and for forcing said inner tubular member inwards for engaging the gripping elements upon a cord or the like passing through said openings, the outer end of said inner tube being reduced for freely engaging against the inner face of said plug. 5
